GAUGE

Herman Heyman, Brooklyn, N. Y.

Application January 20, 1944, Serial No. 519,005

4 Claims. (Cl. 33—184.5)

This invention relates to gauges for printing presses in general.

Among the objects of the present invention it is aimed to provide a simple construction for quickly and expeditiously attaching gauges to the platens of printing presses which will dispense with the necessity of using the gauge pins heretofore extensively used. With the gauge pins heretofore extensively used the tympan sheet was first secured in place on the platen and then the gauge pins secured to the sheet by piercing the same. While the skilled printer after years of experience was enabled to secure these gauge pins to the tympan sheet satisfactorily to suit the ordinary precision required in hand fed printing press work, it was by no means an easy task for the apprentice or new man accurately to position these gauge pins. Furthermore, as a result of use the holes formed in the tympan sheets by the gauge pins became larger with use and consequently the tympan sheets had to be frequently replaced.

According to the present invention, a tympan sheet once secured to the platen would last indefinitely. To meet this requirement, one of the objects of the present invention is to provide a flexible band which can be quickly and expeditiously secured to extend across the tympan sheet with the gauges slidably mounted thereon, so that for an adjustment laterally of the platen it will only be necessary to slide the gauges along the flexible strip and for an adjustment longitudinally of the platen it will only be necessary to change the position of the flexible strip.

It is still another object of the present invention to provide a flexible support adjustably secured to the platen and gauges adjustably mounted on the support for positioning the advanced edge of the sheet to be printed, and an adjustably mounted device on said support associated with a gauge or gauges for positioning one side of the sheet to be printed.

These and other features, capabilities and advantages of the invention will appear from the subjoined detail description of one specific embodiment thereof illustrated in the accompanying drawing, in which

Figure 1 is a perspective of a printing press platen of the type today extensively used with the improved gauge device constituting the present invention secured thereto.

Fig. 2 is an enlarged fragmental section on the line 2—2 of Figure 1.

Fig. 3 is a still further enlarged fragmental plan view of one of the gauges mounted in position.

Fig. 4 is a section on the line 4—4 of Fig. 2.

Fig. 5 is an enlarged fragmental plan showing the attachment for supporting a side gauge.

5 In the embodiment shown, there is provided a printing press platen 1 equipped with the usual U shaped fastening strips 2 and 3 for securing the tympan sheet 4 in place.

The present invention consists essentially of the device now to be described. In the present instance there is provided a flexible strip of metal 5, preferably composed of a suitable rust-proof steel. Excellent results have been obtained when this flexible strip 5 is not over one-half inch in width and about .025 inch in thickness. Preferably to one end of the strip 5 there is secured an L shaped casting 6, the portion 7 being shown as riveted to the strip 5 and the lip 8 being provided with a screw-threaded opening to receive the threaded shank of the set screw or fastening screw 9. To the other end of the strip 5 there is secured a similar L shaped casting 10 having its portion 11 riveted to the upper face of the strip 5 and the portion 12 extending down parallel to the outer face of the portion 13 of the strip 3. In the portion 12 of the casting 10, there is preferably provided a screw threaded opening to receive the threaded shank 14 of the fastening screw 15. These fastening screws 9 and 15 in the present instance have wing heads 16 with openings 17 therein. In some instances it may be desirable to provide nuts 18 to engage either the outer or inner faces of the portions 8 and 12. In the present instance the nuts 18 engage the outer faces of the portions 8 and 12.

35 On the strip 5 there are slidably mounted one or more gauge devices 19, two being shown in the present instance.

The gauge device, see Fig. 3, consists essentially of a plate 20 having an upturned flange 21 at its rear end intermediate the two extensions 22 and 23. At its front edge this plate has an upturned flange 24 intermediate the extensions 25 and 26. The extensions 25 and 26 extend forwardly of the flange 24 and have at their front ends the upturned flanges 27 and 28. These flanges 27 and 28 in the use of this device constitute the stops against which the advanced edge of the sheet being printed rests. The upturned flanges 21 and 24, on the other hand, constitute abutments for the fastening means which in the present instance consist primarily of a U shaped yieldable wire 29 in the shape of a hair pin. The two legs 30 and 31 of the wire 29 extend through openings in the flanges 24 and 21, as shown. These openings are sufficiently close to the main web portion 32 of the

plate 20 so that, especially when the legs 30 and 31 are bowed, as shown in Fig. 4, the bowed portions of the legs 30 and 31 will frictionally engage the upper face of the strip 5 when the gauge device is mounted upon the strip 5 as shown in Figure 1, that is, with the web portion 32 disposed adjacent the lower face of the strip 5, and the flanges 24 and 21 adjacent the edges of the strip 5, and the wire 29 extending through the openings in the flanges 24 and 21 so that its bowed legs 30 and 31 will engage the upper face of the strip 5.

The plates 20 are preferably composed of a thin durable metal such as spring steel or the like. Excellent results have been obtained when this metal does not exceed .025 inch in thickness.

The distance between the portions 8 and 12 when secured to the strip 5 is sufficient to extend beyond the width of the platen 1 and its fastening strips 2 and 3 as shown in Figs. 1 and 2. The lower faces of the rivets connecting the castings 6 and 10 to the strip 5 are preferably so accurately finished that the lower face of the strip 5 will snugly engage the upper face of the tympan sheet 4 adjacent the castings 6 and 10.

The lengths of the threaded shanks of the fastening screws 9 and 15 are preferably long enough depending upon the size of platen 1 with which the device is to be used, so that they may either position the strip 5 when the portions 8 and 12 are disposed adjacent to the arms 13 of the fastening strip 3, or adjacent the arms 33 and 34 of the fastening strip 2 or adjacent the free edges 35 and 36 of the platen 1 intermediate the fastening strips 2 and 3.

The wires 29 not only serve frictionally to anchor the gauges 19 in position on the strip 5, but also serve as guides that may be adjustable. As an instance, when the printing is disposed close to the advanced edge of the sheet it may be desirable to have the wire 29 assume the position shown in full lines in Fig. 3, whereas when the printing at the advanced edge of the sheet is remote therefrom, in the interest of affording a more extended guide, the wire 29 may be slidably positioned to assume the dash and dot line position shown in Fig. 3.

In view of the foregoing, it is obvious that the two gauges 19 shown in Figure 1 may be moved to assume different positions on the strip 5 according to the location of the sheet to be printed, and similarly the strip 5 in turn may quickly and expeditiously be positioned to assume different positions on the platen 1 by the single manipulation of the screw 15, initially to free the strip 5 before positioning the same and then again to secure the same at the new position determined. The opening 17 in the wing head 16 of the screw 15 is provided to enable the printer to use any suitable tool or even a nail to quickly and expeditiously secure the screw 15 in position.

In some instances, it may also be desirable to provide gauges for engaging and positioning one side of the sheet to be printed. In such cases, the arm 37 is provided, which consists preferably of a metal strip of .025 inch in thickness and of some suitable durable metal such as spring steel or the like. This arm 37 in the present instance is provided with two pairs of projections 38, 39 and 40, 41, bent therefrom to engage the opposite edges of the strip 5, the projections 38 and 39 engaging the front edge and the projections 40 and 41 engaging the rear edge. The arm 37 is also provided with an opening 42 of about one-eighth inch in diameter, sufficient to clear and permit

one of the heads or buttons 43 formed on the strip 5 to pass therethrough. These buttons 43 are undercut as shown in Fig. 2, and when one of these buttons 43 extends through the opening 42 in the strip 37, the undercut will clear the upper face of the strip 37 to receive the hook portion 44 of the hook 45 pivotally connected at 46 to the upper face of the strip 37. The strip 37, similar to the strip 5, is about one-half inch in width so that it may receive a gauge device such as the gauge device 19 described. When a gauge device 19 is mounted on the strip 37, in order to function as positioning means for the side of the sheet to be printed, the stops 27 and 28 preferably face inwardly as shown in Figure 1.

Excellent results have been obtained when the heads 43 are spaced about three-eighths inch from one another, and also when these heads 43 are only formed on the left hand end of the strip 5 as shown in Figure 1. It is believed desirable to have the heads mounted on this left hand end of the strip 5 since practice has shown that the average printer positions the sheet to be printed with respect to the left hand edge and of course upper or advanced edge.

It is, of course, conceivable that a printer who is physically handicapped might prefer to have the heads 43 on the right hand end of the strip 5 with a view to positioning the sheet by means of its right hand edge and advanced edge instead of by means of its left hand edge and advanced edge.

While in some instances it may be sufficient in the interest of speed to manipulate only one wing head 16 and a nut 18 to reposition the strip 5, it is, of course, obvious that cases may arise where it may be desirable to manipulate the wing heads of both screws 9 and 15.

It is obvious that various changes and modifications may be made to the details of construction without departing from the general spirit of the invention as set forth in the appended claims.

I claim:

1. The combination of a printing press platen, a supporting flat strip of metal, means for connecting the strip to said platen, and gauges adjustably mounted on said strip, each of said gauges including a plate engaging the lower face of said strip, upwardly extending projections at the front of said plate to form positioning stop faces for the sheet to be printed, upwardly extending flanges on said plate clearing the front and rear edges of said supporting strip, there being openings formed in said flanges, and a U shaped wire with its shanks extending through the openings in said flanges, the shanks being bowed to frictionally engage the upper face of the supporting strip frictionally to anchor the gauge in position on said supporting strip.

2. The combination of a printing press platen, a supporting strip, means for removably connecting said strip to said platen, and gauges slidably mounted on said strip each of said gauges including a plate engaging the lower face of the strip, portions of said plate forming positioning stops, other portions of said plate forming abutments, and a U shaped wire extending through said abutments and frictionally anchoring the gauge to said strip, the wire being movably mounted in said abutments to enable its looped end to extend a greater or less distance according to the free margin of the sheet to be printed.

3. The combination of a printing press platen, a supporting flat strip of metal, means for con-

necting the strip to said platen, and gauges adjustably mounted on said strip, each of said gauges including a plate engaging the lower face of said strip, upwardly extending projections at the front of said plate to form positioning stop faces for the sheet to be printed, upwardly extending flanges on said plate clearing the front and rear edges of said supporting strip, and a friction creating anchoring member mounted on said flanges to frictionally engage the upper face of the supporting strip frictionally to anchor the gauge in position on said supporting strip. 10

4. The combination of a printing press platen, a supporting strip, means for connecting said strip to said platen, and gauges slidably mounted on said strip each of said gauges including a plate engaging the lower face of the strip, portions of said plate forming positioning stops, other portions of said plate forming abutments, and means mounted on said abutments and frictionally anchoring the gauge to said strip. 5
